(57) **CLAIM**

The ornamental design for a transaction card, as shown and described.

DESCRIPTION

FIG. 1 is an isometric view of the transaction card showing our new design;

FIG. 2 is a top view thereof;

FIG. 3 is a bottom view thereof;

FIG. 4 is a first side view thereof;

FIG. 5 is a second side view thereof;

FIG. 6 is a first end view thereof; and,

FIG. 7 is a second end view thereof.

The broken lines in the drawings depict portions of the transaction card that form no part of the claimed design.
